UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

FLUID-COMPRESSING APPARATUS.

1,388,670.

Specification of Letters Patent. Patented Aug. 23, 1921.

Application filed January 21, 1918. Serial No. 212,936.

To all whom it may concern:

Be it known that I, ROBERT SUCZEK, subject of the Emperor of Austria, residing in Philadelphia, in the county of Philadelphia and the State of Pennsylvania, have invented new and useful Improvements in Fluid-Compressing Apparatus, of which the following is a specification.

My invention relates to apparatus for compressing elastic fluid and involves the ejector principle in accordance with which an elastic motive fluid, such as steam, is expanded, effecting jet formation which entrains the elastic fluid to be compressed, the mixture of motive and entrained fluids then traversing a passage in which velocity is converted into pressure.

In accordance with my invention, disadvantages (inter alia friction losses between stages and rise of temperature of mixture discharged from an earlier into a later stage) of two or more stage ejector apparatus are overcome by associating, as in a single stage ejector, a plurality of nozzle structures co-acting with a common diffuser structure or combining tube structure.

In accordance with my invention, one of the nozzle structures projects well into the diffuser structure, while another of the nozzle structures terminates short of the entrance to the diffuser structure, or terminates substantially at the entrance to the diffuser structure, or projects somewhat into the diffuser structure but to less distance than the first mentioned nozzle structure.

Further in accordance with my invention, there is formed between the interior of the combining tube or diffuser structure and the longer nozzle structure which projects well thereinto a preferably converging passage whose smallest cross sectional area is greater than the total outlet area of the other or shorter nozzle structure and smaller than the total outlet area of the longer nozzle structure, and smaller than the cross sectional area of the throat of the diffuser structure, the cross sectional area of said throat of the diffuser structure preferably being less than the total outlet area of the longer nozzle structure.

Further in accordance with my invention, the motive fluid consumed by the longer nozzle structure is greater than consumed by the shorter nozzle structure, and preferably the

relation is such that the motive fluid consumed by the shorter nozzle structure is less than 25 per cent. of the total motive fluid consumed by both the long and short nozzles; and in accordance with my invention, this relation may be obtained by making the total throat area of the shorter nozzle structure less than 25 per cent. of the total throat area of both long and short nozzle structures, or, differently stated, the total throat area of the short nozzle structure is one-third or less of the total throat area of the long nozzle structure.

Further in accordance with my invention, the mixture of entrained fluid with the motive fluid delivered by the shorter nozzle structure is cooled, by extraction of heat therefrom while in the diffuser or combining tube structure; and the motive fluid of the long nozzle structure absorbs heat.

My invention resides in the features of structure and combination hereinafter described and claimed.

For an illustration of some of the various forms my invention may take, reference is to be had to the accompanying drawings, in which:

Figure 1 is a longitudinal sectional view through an ejector embodying my invention.

Fig. 2 is a plan view of the nozzle supporting plate of Fig. 1.

Fig. 3 is a longitudinal sectional view, on enlarged scale, of a portion of the main or longer nozzle structure of Fig. 1.

Fig. 4 is a top plan view of the nozzle structure shown in Fig. 3.

Fig. 5 is a bottom plan view of the nozzle structure shown in Fig. 3.

Fig. 6 is a side elevational view of the core structure of Fig. 3.

Fig. 7 is a longitudinal sectional view, partly in elevation, of a modified core structure.

Fig. 8 is a bottom plan view of the structure shown in Fig. 7.

Fig. 9 is a longitudinal sectional view of a modified form of ejector embodying my invention.

Figs. 10 and 11 are fragmentary longitudinal sectional views of modified forms of ejector apparatus embodying my invention.

Fig. 11^a is a plan view illustrating the relative positions of the long and short nozzle structures of Fig. 11 at their upper ends.

Fig. 12 is a fragmentary longitudinal sectional view of a further modification embodying my invention.

It will be understood that the main or longer nozzle structure may consist of one or a plurality of nozzles formed within a unitary structure, or may consist of a plurality of structurally independent nozzles; and it will be understood that the auxiliary or shorter nozzle structure consists of a plurality of nozzles, which may be considered a group, and within such group the nozzles may be of the same or different lengths.

My ejector apparatus may be utilized in various relations, and is utilizable to advantage for producing high vacuum, as of the order of $28\frac{1}{2}$ to $29\frac{1}{2}$ inches of mercury (Hg.). Such vacuum may be produced and maintained in condensers such as those condensing the exhaust steam from turbines or steam engines, and the air so exhausted may be raised in pressure or compressed to substantially atmospheric pressure, or to other suitable pressure.

Referring to Fig. 1, the air or other elastic fluid to be compressed is delivered by any suitable conduit, not shown, to the port 1 of the suction chamber 15. The elastic motive fluid under pressure, as steam, is delivered through the port 2 into the steam chamber 3, which is separated from the suction chamber by the nozzle plate 14 carrying the long and short nozzle structures 16 and 4, both nozzle structures being of the expansion nozzle type, that is, divergent beyond their throats, to effect expansion of the motive fluid and thereby convert its pressure into velocity, whereby there will issue from their outlets motive fluid jets consisting of motive fluid traveling at high velocity. The short nozzle structure comprises the circular series of nozzles 4, disposed, as indicated in Fig. 2, around the central nozzle structure 16 whose throat is 12. The short nozzles 4 are shown as threaded into the plate 14, while the nozzle structure 16 is integral therewith, though it will be understood also that the long nozzle structure may be separate from the plate 14 and threaded thereto.

In this example the short nozzle structure terminates short of the entrance to the common diffuser structure or combining tube structure 25 comprising the sections 22, 8 and 10, the structure being convergent-divergent, having the discharge outlet at 11, and in this example having the throat or regions of smallest cross section of some length as indicated at 9, though it will be understood that the elongated throat 9 may be omitted and the adjacent ends of the sections 8 and 10 may immediately adjoin, as well understood in the art and as indicated in later figures hereof. On the other hand, the main or long nozzle structure projects well or far into the diffuser structure, and

there is formed between the exterior of the nozzle structure 16 and the interior of the diffuser structure a convergent passage 7 whose throat or region of smallest cross section is indicated at 43.

70

The long or main nozzle structure 16 may be a common or ordinary expansion nozzle, such as used in this art, and in such case will have a conical or divergent portion below the throat 12 with its outlet at the lower end 75 at 23, both the throat and the outlet being generally of circular cross section.

In order, however, to increase the lateral entraining surface of the jet of motive fluid issuing from the nozzle structure, a core 5 80 may be disposed within the conical divergent portion of the nozzle structure below the throat 12, such core structure being indicated in Fig. 6 as having the passages, channels, or grooves 13, of rectangular, triangular or other suitable cross section, terminating at their upper ends in the knife edges 24 which, as indicated in Figs. 1 and 3, are deposited below the throat 12, whereby the throat 12 is common to all the passages 13; 90 the passages 13 are closed longitudinally by the outer conical shell 16 of the nozzle structure, whereby a circular series of jets issues from the nozzle structure, the total area of the jets being thus greater than the area of a single jet, and so affording greater lateral surface for entraining the elastic fluid to be compressed.

In Figs. 7 and 8 the nozzle core is of modified structure in that through the center of 100 the core 18 extends an expansion nozzle passage 25^a having its smallest cross sectional area at 19 and its outlet at 17. Upon the core 18 are the longitudinally extending ribs or core members 20 between which are the 105 grooves, channels or passages 21, in this instance of triangular cross section. While the central nozzle passage is shown as of greater length than the passages 21, it will be understood that they may be of substantially equal length. This core structure may be inserted in a nozzle member, similar to 16, Figs. 1 and 3, in which case the nozzle passage 25^a will terminate even farther within the diffuser structure than the core 115 structure 16 of Fig. 1. By so employing the extra length nozzle passage, as 25^a, the ratio of compression of the entire ejector apparatus will be somewhat increased, that is, the quotient of the absolute pressure at the 120 discharge of the ejector divided by the absolute pressure in the suction chamber 15 will be a greater quantity. Such an arrangement is particularly suitable when the ejector is working against a higher back pressure.

Referring to Fig. 9, a generally similar structure is shown comprising the suction chamber 26 having the suction inlet or port 27. Elastic motive fluid, as steam, is intro- 130

duced through the port 28 into the steam chamber 29, which is separated from the suction chamber 26 by the nozzle plate 30 into which are threaded the long and short nozzle structures. The short nozzle structure comprises the circular series of short expansion nozzles 31, which in this case are inclined inwardly toward the axis of the diffuser structure or combining tube structure 32; and they also extend to or into the convergent section 33 of the diffuser 32, which comprises said convergent section 33 and the diverging section 34 meeting at the throat 9, the discharge end of the diffuser being at the lower end of the section 34. The long nozzle structure is in general similar to the nozzle structure 16 of Fig. 1, and comprises the member 36 projecting well or far into the diffuser section 33, and having the core 38 having the outwardly extending ribs 40, between which and the shell 36 are formed channels or nozzle passages 41. In this instance, however, each nozzle passage 41 has its own separate throat 37 whose upper end is at 39. The shell or nozzle body 36 may, as indicated at 42, be reduced in diameter suitably to determine the cross sectional area of the passage 43, corresponding with passage 43 of Fig. 1. Between the exterior of the nozzle structure 36 and the interior of the diffuser section 33 is formed a converging passage 35 whose region of smallest cross sectional area is at 43.

Referring to Fig. 10, the arrangement is again in general similar to Fig. 1. The diffuser structure or combining tube structure 25 comprises the converging section 8 and diverging section 10 meeting at the throat 9, the section 8 having a converging passage 7 between its inner wall and the outer wall of the nozzle structure 16 having the divergent nozzle passages 13 each having, if desired, its own throat 37 as in Fig. 9. In this case the short nozzle structure comprises a group of nozzles of different lengths, the shortest nozzles 4 terminating short of the entrance to the diffuser structure, while the long nozzles 31 of the group extend into the diffuser structure, and still further nozzles, as 44, terminating at the entrance to the diffuser structure. The purpose of this illustration is to indicate that the short nozzle structure may comprise nozzles of different lengths. As indicated further, some of the nozzles, as 31, may be inclined, while the others may have their axes parallel to the axis of the diffuser structure 25.

Referring to Fig. 11, the arrangement is again in general similar to that indicated in Fig. 1. In this case, however, the long nozzle structure comprises a plurality of separate nozzles 45 projecting well into the converging portion 8 of the diffuser structure 25 and having their throats at 46. The

passage 47 from the entrance to the converging section 8 to the lower ends of the nozzles 45 is convergent, and the smallest cross sectional area of such passage is adjacent the lower ends of the nozzles 45, such region of smallest cross section corresponding with the passages 43 of Figs. 1, 9 and 10.

The short nozzle structure comprises short inclined nozzles 48 having their throats at 49 and projecting into the diffuser structure.

As indicated in Fig. 11, the nozzles 45 are arranged in a circular series, as are also the nozzles 48.

Referring to Fig. 12, the long nozzle structure has a core structure of the character indicated in Fig. 7, whereby the nozzle passage 17 has its outlet farther within the diffuser structure 25 than the outlets of the passages 21. The short nozzle structure comprises a group of nozzles comprising the short nozzles 4 terminating short of the entrance to the diffuser structure, and nozzles 44 reaching the entrance of the diffuser structure, and longer nozzles 31 entering the diffuser structure, the purpose of this illustration being to indicate that the short nozzle structure may have nozzles of any suitable length falling short of or extending into the diffuser structure.

95

The mode of the operation of the structures shown in Figs. 1, 9, 10, 11 and 12 is as follows:

The air or other elastic motive fluid to be raised in pressure enters the suction chambers 15 or 26 and comes into contact with the jets of motive fluid, as steam jets, issuing from a short nozzle structure, the mixture then passing into the convergent passage 7 or 35, and in traversing the same undergoes compression or rises in pressure, or increases in velocity, and after traversing the narrow passage or throat 43 is acted upon by the steam or other motive fluid jet or jets issuing from the long nozzle structure, with the result that the mixture undergoes further compression in the diffuser structure, from which it is discharged, at the lower end of the diffuser structure, at the desired higher pressure.

115

For example, the pressure of the air or other elastic fluid entering the suction chamber may be of the order of one-half to one and one-half inches of mercury, absolute, and upon reaching the throat or passage 43 may have attained a higher pressure, but less than eight inches of mercury absolute. Beyond the passage or throat 43 the pressure is still further increased to the desired or suitable pressure existing at the discharge end of the diffuser structure, such final pressure being for example, atmospheric pressure.

120

It is preferred as to all the arrangements described and illustrated that the cross sec-

125

130

tional area of the passage or throat 43 shall be larger than the sum of the areas at the outlets of the nozzles of the short nozzle structure; and that the cross sectional area 5 of the throat or passage 43 shall be smaller than the total outlet area of the long nozzle structure. That is, for example, the cross sectional area of the passage or throat 43 is preferably made larger than the sum of the 10 areas of the passages of the nozzles 4, Fig. 1, at their lower or discharge ends; and the cross sectional area of the passage or throat 43 is preferably smaller than the sum of the areas of the nozzle passages 13, Fig. 1, at 15 their lower or discharge ends.

It is also preferred as to all the structures described and illustrated that the total area at the outlet or outlets of the long nozzle structure shall be greater than the cross sectional area of the diffuser or combining tube 20 throat 9, Figs. 1, 10, 11 and 12, or 9^a Fig. 9.

And it is further preferred as to all the structures illustrated and described that the cross sectional area of the diffuser throat 9 25 or 9^a shall be greater than the cross sectional area of the passage or throat 43.

It is also preferred as to all structures described and illustrated that the total of the throat areas of the short nozzle structure 30 shall be less than 25 per cent. of the total of the throat areas of the long and short nozzle structures combined. That is to say, the total throat area of the long nozzle structure may be three or more times the 35 total of the throat areas of the short nozzle structure, whereby the total motive fluid employed in the long nozzle structure will be three or more times the total motive fluid consumed in the short nozzle structure.

40 In the long nozzle structures the expansion of the motive fluid therein may effect a decrease in temperature of the motive fluid as it approaches the discharge or outlet end of the nozzle structure, with the result that

45 the long nozzle structure may partake of a temperature lower than the mixture of entrained fluid with the motive fluid discharged from the short nozzle structure; and since this mixture passes in contact with 50 the long nozzle structure before reaching the discharge end of the long nozzle structure or passage 43, the long nozzle structure will effect an absorption of heat from that mixture, with the result that the motive fluid

55 in traversing the long nozzle structure, otherwise tending to become moist, may become dry and saturated before leaving the long nozzle structure, with a consequent gain in economy. On the other hand, the mix-

60 ture of entrained fluid with the motive fluid discharged from the short nozzle structure in passing from the entrance of the diffuser structure to the passage or throat 43 is cooled, with the result that its volume will 65 be diminished and the entraining action of

the motive fluid issuing from the nozzle structure will be improved or increased.

While I have herein disclosed means within the ejector structure, particularly within the diffuser or combining tube structure, for 70 cooling a mixture of motive and entrained fluids, the same is not herein claimed, but is claimed in my co-pending application Serial No. 469,164, filed May 13, 1921.

In the appended claims, "diffuser" or "diffuser structure" is referred to or employed as the equivalent of or synonymous with "combining tube" or "combining tube structure." And the terms "long" and "short" as applied in the appended claims to the 80 nozzle structures refer to the fact that the discharge outlet or outlets of the one nozzle structure is or are disposed nearer the throat 9 or 9^a of the common diffuser structure or combining tube structure than the outlet or 85 outlets of the other nozzle structure.

What I claim is:

1. An ejector comprising central nozzle structure, and a group of nozzles surrounding said nozzle structure, the total throat 90 area of said central nozzle structure being greater than the total throat area of said group of nozzles.

2. An ejector comprising diffuser structure, short nozzle structure, and long nozzle 95 structure discharging motive fluid nearer the throat of said diffuser structure than said short nozzle structure, the total throat area of said long nozzle structure being greater than the total throat area of said short nozzle 100 structure.

3. An ejector comprising diffuser structure, short nozzle structure, and long nozzle structure extending into said diffuser structure and discharging nearer the throat thereof than said short nozzle structure, the total throat area of said short nozzle structure being less than the total throat area of said long nozzle structure.

4. An ejector comprising diffuser structure, short nozzle structure comprising a group of nozzles, and long nozzle structure projecting into said diffuser structure and discharging nearer the throat thereof than said nozzles of said short nozzle structure, 110 the total throat area of said long nozzle structure being greater than the total throat area of the nozzles of said short nozzle structure.

5. An ejector comprising diffuser structure, long nozzle structure projecting well into said diffuser structure, and short nozzle structure projecting into said diffuser structure, the total throat area of said short nozzle structure being less than the total throat 125 area of said long nozzle structure.

6. An ejector comprising diffuser structure, long nozzle structure projecting well into said diffuser structure, and short nozzle structure comprising a plurality of nozzles 130

projecting into said diffuser structure, the total throat area of said short nozzle structure being less than the total throat area of said long nozzle structure.

5 7. An ejector comprising diffuser structure, long nozzle structure projecting well into said diffuser structure and comprising a plurality of motive fluid conducting passages, and short nozzle structure comprising

10 a plurality of nozzles discharging into said diffuser structure, the total throat area of said short nozzle structure being less than the total throat area of said long nozzle structure.

15 8. An ejector comprising central nozzle structure, and a group of nozzles surrounding said nozzle structure, the total throat area of said central nozzle structure being at least three times as great as the total 20 throat area of said group of nozzles.

9. An ejector comprising diffuser structure, long nozzle structure projecting well into said diffuser structure, and short nozzle structure, the total throat area of said 25 long nozzle structure being at least three times as great as the total area of said short nozzle structure.

10. An ejector comprising diffuser structure, long nozzle structure projecting well 30 into said diffuser structure, and short nozzle structure comprising a plurality of nozzles, the total throat area of said long nozzle structure being at least three times as great as the total area of said short nozzle structure.

11. An ejector comprising diffuser structure, long nozzle structure projecting into 35 said diffuser and comprising a plurality of motive fluid conducting passages, and short nozzle structure comprising a plurality of

40 nozzles discharging into said diffuser structure, the total throat area of said long nozzle structure being at least three times as great as the total throat area of said short nozzle structure.

45 12. Ejector apparatus comprising diffuser structure, long nozzle structure projecting into said diffuser structure and spaced therefrom to form a passage whose smallest cross sectional area is not greater than the total outlet area of said long nozzle structure, and short nozzle structure discharging through said passage.

13. Ejector apparatus comprising diffuser 50 structure, long nozzle structure projecting into said diffuser structure and spaced therefrom to form a passage whose smallest cross sectional area is less than the total outlet area of said long nozzle structure, and short nozzle structure discharging through said passage.

55 14. Ejector apparatus comprising diffuser structure, long nozzle structure projecting into said diffuser structure and spaced

therefrom to form a passage whose smallest 65 cross sectional area is not greater than the total outlet area of said long nozzle structure, and short nozzle structure extending into said diffuser structure and discharging through said passage.

70 15. Ejector apparatus comprising diffuser structure, long nozzle structure projecting into said diffuser structure and spaced therefrom to form a passage whose smallest cross sectional area is less than the total outlet 75 area of said long nozzle structure, and short nozzle structure discharging through said passage, said diffuser structure decreasing in cross section from its entrance to said passage.

80 16. Ejector apparatus comprising diffuser structure, long nozzle structure projecting into said diffuser structure and spaced therefrom to form a passage whose smallest cross sectional area is not greater than the total 85 outlet area of said long nozzle structure, and short nozzle structure extending into said diffuser structure and discharging through said passage, said diffuser structure decreasing in cross section from its entrance to said 90 passage.

17. An ejector comprising diffuser structure, long nozzle structure projecting into said diffuser structure and spaced therefrom to form a passage decreasing in cross section 95 from the entrance of said diffuser structure and whose smallest cross sectional area is not greater than the total outlet area of said long nozzle structure, and short nozzle structure projecting into said diffuser and 100 discharging into said passage, the total throat area of said short nozzle structure being less than the total throat area of said long nozzle structure.

18. An ejector comprising diffuser structure, long nozzle structure projecting into 105 said diffuser structure and spaced therefrom to form a passage decreasing in cross section from the entrance of said diffuser structure and whose smallest cross sectional area 110 is not greater than the total outlet area of said long nozzle structure, and short nozzle structure comprising a plurality of nozzles projecting into said diffuser and discharging into said passage, the total throat area of 115 said short nozzle structure being less than the total throat area of said long nozzle structure.

19. An ejector comprising diffuser structure, long nozzle structure projecting into 120 said diffuser structure and spaced therefrom to form a passage decreasing in cross section from the entrance of said diffuser structure and whose smallest cross sectional area is not greater than the total outlet area of said long nozzle structure, and short nozzle structure projecting into said diffuser and 125 discharging into said passage, the total

throat area of said long nozzle structure being at least three times as great as the total throat area of said short nozzle structure.

20. An ejector comprising diffuser structure having a throat, long nozzle structure delivering into said diffuser and having a total outlet area greater than the cross sectional area of said diffuser structure at its said throat, and co-acting short nozzle structure delivering into said diffuser structure.

15 21. An ejector comprising diffuser structure having a throat, long nozzle structure projecting into said diffuser and having a total outlet area greater than the cross sectional area of said diffuser structure at its said throat, and co-acting short nozzle structure delivering into said diffuser structure.

22. An ejector comprising diffuser structure having a throat, long nozzle structure 20 delivering into said diffuser and having a total outlet area greater than the cross sectional area of said diffuser structure at its said throat, and co-acting short nozzle structure 25 delivering into said diffuser structure, the total throat area of said short nozzle structure being less than the total throat area of said long nozzle structure.

23. An ejector comprising diffuser structure having a throat, long nozzle structure projecting into said diffuser and having a total outlet area greater than the cross sectional area of said diffuser structure at its said throat, and co-acting short nozzle structure delivering into said diffuser structure, the total throat area of said short nozzle structure being less than the total throat area of said long nozzle structure.

24. An ejector comprising diffuser structure having a throat, long nozzle structure projecting into said diffuser and having a total outlet area greater than the cross sectional area of said diffuser structure at its said throat, and co-acting short nozzle structure delivering into said diffuser structure, said long nozzle structure forming with said diffuser structure a converging passage whose least cross sectional area is less than the total outlet area of said long nozzle structure.

50 25. An ejector comprising diffuser structure having a throat, long nozzle structure projecting into said diffuser and having a total outlet area greater than the cross sectional area of said diffuser structure at its
55 said throat, and co-acting short nozzle structure delivering into said diffuser structure, the total throat area of said short nozzle structure being less than the total throat area of said long nozzle structure, said long
60 nozzle structure forming with said diffuser structure a converging passage whose least cross sectional area is less than the total outlet area of said long nozzle structure.

26. An ejector comprising diffuser structure having a throat, long nozzle structure

projecting into said diffuser and having a total outlet area greater than the cross sectional area of said diffuser structure at its said throat, and co-acting short nozzle structure projecting into said diffuser structure. 70

27. An ejector comprising diffuser structure having a throat, long nozzle structure projecting into said diffuser and having a total outlet area greater than the cross sectional area of said diffuser structure at its said throat, and co-acting short nozzle structure projecting into said diffuser structure, the total throat area of said short nozzle structure being less than the total throat area of said long nozzle structure. 80

area of said long nozzle structure. 80

28. An ejector comprising diffuser structure having a throat, long nozzle structure projecting into said diffuser and having a total outlet area greater than the cross sectional area of said diffuser structure at its said throat, and co-acting short nozzle structure projecting into said diffuser structure, the total throat area of said short nozzle structure being less than the total throat area of said long nozzle structure, said long nozzle structure forming with said diffuser structure a converging passage whose least cross section is less than the total outlet area of said long nozzle structure. 85 90

29. An ejector comprising diffuser structure, long nozzle structure projecting into said diffuser structure, short nozzle structure comprising a plurality of nozzles delivering into said diffuser structure, the total of the outlet areas of said nozzles of said short nozzle structure being smaller than the smallest cross sectional area of the passage between said long nozzle structure and said diffuser structure. 95 100

20. An ejector comprising diffuser structure, long nozzle structure comprising a plurality of nozzle passages projecting into said diffuser structure, short nozzle structure comprising a plurality of nozzles delivering into said diffuser structure, the total of the outlet areas of said nozzles of said short nozzle structure being smaller than the smallest cross sectional area of the passage between said long nozzle structure and said diffuser structure. 115

31. An ejector comprising diffuser structure, long nozzle structure projecting into said diffuser structure, short nozzle structure comprising a plurality of nozzles delivering into said diffuser structure, the total of the outlet areas of said nozzles of said short nozzles structure being smaller than the smallest cross sectional area of the passage between said long nozzle structure and said diffuser structure, and the total throat area of said short nozzle structure being less than the total throat area of said long nozzle structure.

32. An ejector comprising diffuser structure, long nozzle structure comprising a plu- 130

- rality of nozzle passages projecting into said diffuser structure, short nozzle structure comprising a plurality of nozzles delivering into said diffuser structure, the total of the outlet areas of said nozzles of said short nozzle structure being smaller than the smallest cross sectional area of the passage between said long nozzle structure and said diffuser structure, and the total throat area of said long nozzle structure being at least three times as great as the total throat area of said short nozzle structure.
33. Ejector apparatus comprising diffuser structure, long nozzle structure projecting into said diffuser structure and spaced therefrom to form a passage whose smallest cross sectional area is not greater than the total outlet area of said long nozzle structure, and short nozzle structure discharging through said passage, the total outlet area of said short nozzle structure being less than said smallest cross sectional area of said passage.
34. Ejector apparatus comprising diffuser structure, long nozzle structure comprising a plurality of nozzle passages projecting into said diffuser structure, the total outlet area of said long nozzle structure being greater than the smallest cross sectional area of the passage between said diffuser structure and said long nozzle structure, and short nozzle structure discharging through said passage, the total outlet area of said short nozzle structure being less than said smallest cross sectional area of said passage.
35. An ejector comprising diffuser structure having a throat, long nozzle structure delivering into said diffuser structure and having a total outlet area greater than the cross sectional area of the diffuser structure at its said throat, co-acting short nozzle structure delivering into said diffuser structure, the total outlet area of said short nozzle structure being less than the smallest cross sectional area of the passage between said long nozzle structure and said diffuser structure.
36. An ejector comprising diffuser structure having a throat, long nozzle structure comprising a plurality of nozzle passages projecting into said diffuser structure and having a total outlet area greater than the cross sectional area of the diffuser structure at its said throat, co-acting short nozzle structure comprising a plurality of nozzles delivering into said diffuser structure, the total of the outlet areas of the nozzles of the short nozzle structure being less than the smallest cross sectional area of the passage between said long nozzle structure and said diffuser structure.
37. An ejector comprising diffuser structure having a throat, long nozzle structure delivering into said diffuser structure and having a total outlet area greater than the cross sectional area of the diffuser structure at its said throat, co-acting short nozzle structure delivering into said diffuser structure, the total outlet area of said short nozzle structure being less than the smallest cross sectional area of the passage between said long nozzle structure and said diffuser structure, the total outlet area of said short nozzle structure being less than the smallest cross sectional area of the passage between said long nozzle structure and said diffuser structure, the total throat area of said short nozzle structure being less than the total throat area of said long nozzle structure.
38. An ejector comprising diffuser structure, long nozzle structure delivering into said diffuser structure, short nozzle structure delivering into said diffuser structure, the smallest cross sectional area of the passage between said diffuser structure and said long nozzle structure being less than the cross sectional area of said diffuser structure at its throat.
39. An ejector comprising diffuser structure, long nozzle structure delivering into said diffuser structure, short nozzle structure delivering into said diffuser structure, the smallest cross sectional area of the passage between said diffuser structure and said long nozzle structure being less than the cross sectional area of said diffuser structure at its throat, and the total throat area of said short nozzle structure being less than the total throat area of said long nozzle structure.
40. An ejector comprising diffuser structure, long nozzle structure delivering into said diffuser structure, short nozzle structure delivering into said diffuser structure, the smallest cross sectional area of the passage between said diffuser structure and said long nozzle structure being less than the cross sectional area of said diffuser structure at its throat, and the total outlet area of said long nozzle structure being greater than the cross sectional area of said diffuser structure at its throat.
41. An ejector for compressing elastic fluid by elastic motive fluid comprising diffuser structure having convergent and divergent portions, means providing a plurality of divergent motive-fluid-expanding nozzle passages terminating well within the convergent portion of said diffuser structure, and a series of short divergent motive-fluid-expanding nozzles delivering into said convergent portion of said diffuser structure and having discharge outlets at greater distances from the axis of said diffuser structure than the discharge outlets of said first named nozzle passages.
42. An ejector for compressing elastic fluid by elastic motive fluid comprising diffuser structure having convergent and divergent portions, means providing a plurality of divergent motive-fluid-expanding nozzle passages terminating well within the convergent portion of said diffuser structure, and a series of short divergent motive-fluid-expanding nozzles delivering into said

convergent portion of said diffuser structure and having discharge outlets at greater distances from the axis of said diffuser structure than the discharge outlets of said first 5 named nozzle passages, the amount of motive fluid traversing said first named nozzle passages being more than three times the motive fluid traversing said short nozzles.

43. An ejector comprising a plurality of 10 nozzle structures, a tubular diffuser common to them, one of said nozzle structures projecting into said diffuser and spaced therefrom to form a throat, another of said nozzle structures delivering to said throat, said 15 diffuser having a main throat passing the motive fluids from said nozzle structures and the entrained fluid, the quantity of motive fluid consumed by said one nozzle structure being substantially three times the amount 20 of motive fluid consumed by said other nozzle structure.

44. An ejector comprising a plurality of nozzle structures, a tubular diffuser common to them, one of said nozzle structures projecting into said diffuser and spaced therefrom to form a throat, another of said nozzle structures delivering to said throat, said diffuser having a main throat passing the motive fluids from said nozzle structures and 25 the entrained fluid, the area of said first named throat being greater than the total outlet area of said other nozzle structure.

45. An ejector comprising a plurality of nozzle structures, a tubular diffuser common 30 to them, one of said nozzle structures projecting into said diffuser and spaced therefrom to form a throat, another of said nozzle structures delivering to said throat, said diffuser having a main throat passing the 35 motive fluids from said nozzle structures and the entrained fluid, the total area of the outlet of said one nozzle structure being greater than the area of said first named throat.

46. An ejector comprising a plurality of 40 nozzle structures, a tubular diffuser common to them, one of said nozzle structures projecting into said diffuser and spaced therefrom to form a throat, another of said nozzle structures delivering to said throat, said diffuser having a main throat passing the 45 motive fluids from said nozzle structures and the entrained fluid, the area of said second named throat being greater than the area of said first named throat.

47. An ejector comprising a plurality of nozzle structures a tubular diffuser common 50 to them, one of said nozzle structures projecting into said diffuser and spaced therefrom to form a throat, another of said nozzle structures delivering to said throat, said diffuser having a main throat passing the 55 motive fluids from said nozzle structures and the entrained fluid, the total area of the outlet of said one nozzle structure being

greater than the area of said second named 65 throat.

48. Expansion nozzle structure comprising a member having within it a plurality of passages diverging from each other and themselves increasing in cross sectional area 70 in the direction of flow of fluid therethrough.

49. Expansion nozzle structure comprising a member having within it a plurality of passages diverging from each other and themselves increasing in cross sectional area 75 in the direction of flow of fluid therethrough, and a central divergent passage.

50. Expansion nozzle structure comprising a member having within it a plurality of 80 passages diverging from each other and themselves increasing in cross sectional area in the direction of flow of fluid therethrough, and a central divergent passage, said last named passage terminating beyond the outlets of said first named passages.

51. Expansion nozzle structure comprising an envelop member having a divergent passage, and a divergent core member fitting within said passage and having upon its surface a series of passages diverging from each 90 other and themselves divergent.

52. Expansion nozzle structure comprising an envelop member having a divergent passage, and a divergent core member fitting within said passage and having upon its 95 surface a series of passages diverging from each other and themselves divergent, said core member having a co-axial divergent passage.

53. Expansion nozzle structure comprising 100 an envelop member having a divergent passage, and a divergent core member fitting within said passage and having upon its surface a series of passages diverging from each other and themselves divergent, 105 said core member having a central diverging passage having an outlet beyond the outlet of said first named passages.

54. Ejector apparatus for compressing 110 elastic fluid by elastic motive fluid comprising diffuser structure, long and short nozzle structures for expanding motive fluid, the long nozzle structure projecting into said diffuser structure, and the motive fluid discharged by the short nozzle structure effecting preliminary compression within the diffuser structure of the elastic fluid to be compressed before reaching the outlet of the long nozzle structure.

55. Ejector apparatus for compressing 120 elastic fluid by elastic motive fluid comprising diffuser structure, long and short nozzle structures for expanding motive fluid, the long nozzle structure projecting into said diffuser structure, the total throat area of the 125 long nozzle structure being greater than the total throat area of the short nozzle structure, and the motive fluid discharge by the

short nozzle structure effecting preliminary compression within the diffuser of the elastic fluid to be compressed before reaching the outlet of the long nozzle structure.

5 56. Ejector apparatus for compressing elastic fluid by elastic motive fluid comprising diffuser structure, long and short nozzle structures for expanding motive fluid, the long nozzle structure projecting into said

10 diffuser structure, and the motive fluid dis-

charged by the short nozzle structure effecting within the diffuser structure preliminary compression of the elastic fluid to be compressed from a pressure less than three inches of mercury absolute to a pressure less than eight inches of mercury absolute before reaching the outlet of the long nozzle structure. 15
